UNITED STATES PATENT OFFICE

WALTER PERKS, OF LONDON, ENGLAND, ASSIGNOR TO WILLIAM VICARS, OF ROSE BAY,
NEAR SYDNEY, AUSTRALIA

DEBURRING MACHINE

Application filed March 1, 1928, Serial No. 258,397, and in Australia July 18, 1927.

This invention relates to machines for removing burrs, seeds, and other entangled matter from wool on sheep skins and from hair or fur or skins taken from other animals.

5 It relates in particular to deburring machines of the type in which the wool, hair, or fur on the outer side of skins is acted on by spreaders and beaters which are fixed on the peripheral surface of a rotating drum.

10 In the machine in which the present invention consists, the skins in either wet or dry condition are hung over and clamped to carrier boards, and these boards are drawn vertically upwards between fast rotating drums which are armed with parting blades and beaters. The drums are adjustable for clearance required for the passage of the skin clad boards between them, and water is sprayed on the skin whilst it is being acted on by the

20 parting blades and beaters on the drums. The carrier boards are suspended by top corner lugs on continuous chain flights. The skins are hung over the boards, and claw links in the chains pick up the boards as they are fed into the machine over a slideway, and carry them up between the drums, finally delivering them onto a take-off slideway. The deburred skins may be subjected to a finishing treatment in a following machine of like construction. Finally, the clamps are freed and the deburred skins removed from the boards, and the boards are then returned to the starting point to be re-used to carry other skins through the machine or machines.

25 35 In the accompanying drawings:—

Fig. 1 is a longitudinal vertical section through the machine;

Fig. 2 is a front end elevational view;

40 Fig. 3 is a fragmentary longitudinal sectional elevation;

Fig. 4 shows three fragmentary end elevational views of the parting knuckles and beaters with which the drum discs are armed; and

45 Fig. 5 is a perspective view of one of the discs. The drums are built up of assemblies of these discs keyed on a shaft, with the knuckles arranged in helical relation.

50 The skins 10 are hung on the carrier boards 11 with the wool, hair or fur side outward,

and they are secured against slipping by means of clips or clamps 12 of any convenient pattern. The boards 11 are provided with lugs 13 extending from their top corners; the boards 11 are suspended on these 55 lugs 13 in their passage through the machine, 14 represents feed-in runways, and 15 delivery runways, 16—16 are flights of continuous chain belts containing hook links 17 at intervals; these links are adapted for picking up 60 the lugs 13 and carrying the skin loaded boards through the machine. 18 are driver sprocket wheels, 19 top carrier sprocket wheels, and 20 tensioning jockey sprocket wheels over which the chain flights 16—16 65 run. The jockey sprockets 20 have slide bearings 21 and screw adjusters 22, by setting which the chain flights are held at desirable tension.

23 and 24 are the deburring drums, and 70 25 and 26 mangle rollers (smooth faced) located above and parallel to them. 27 are vertical guideways in the side frames 28 in which the lugs 13 run during the course of vertical movement of the skin loaded boards 75 through the machine. 29 are horizontal slides which carry the sliding bearings 30 for the shafts 47 of the drums 23 and 24. 31 are helical springs bearing against the sliding bearings 30 and having screw adjusted abutments 32. 33 are similar slides for the axle slide bearings of the rollers 25—26, 36 are tensioning springs acting to force these rollers towards each other, and 37 are screw adjusted abutments for the springs 36. 38 are 80 spacing wedges for regulating the clearance distance between the drums 23 and 24; they work between ball bearings 46 which are fitted on the drum shafts 47. 49 are compensating levers which are keyed on the ends of 85 a cross shaft 50 and connected together by a rod 147. 51 are slots in the levers 49, which engage offset pins 52 fixed in the sides of the links 53; the wedges 38 are suspended by these links, and their position is readily 90 adjusted by an operative, through the bar 147 and levers 49 which counterbalance the weight of the wedges. Each of the deburring drums 23—24 is built up of an assembly of 95 knuckle discs (Fig. 5) fixed axially on the 100

drum shaft 47 and arranged so that the beaters 54 are disposed in helical order (see Figs. 2 and 3) on the peripheries of the drums. Usually, three such beaters 54 are fitted on each disc. One of these beaters 54a is set erect, and the others 54b and 54c, are offset to left and right respectively. The parting knuckles 60, 61, and 62 should also be similarly set to centre and offset to the sides respectively. The beaters 54 are tubiform, or they are cupped on their leading faces; they are best made by riveting, bolting or otherwise suitably attaching the ends of U-shaped metal loops to the sides of the parting knuckles 60, 61, 62. Their leading faces are tapered thin to blunt edges. The leading edges of the parting knuckles 60, 61, 62 are similarly trimmed to blunt edges, and two of them are offset in correspondence with the offset of the beaters which they carry. Each beater is thus preceded by a parting knuckle which spreads the wool, hair or fur apart to allow the beater to operate through it and not merely against the top of it, and so to effectively engage and tear out the entangled burrs. 41 is a drive shaft for the chain flights. 42 and 43 are countershafts carrying pulleys 44-45, and 146 are pulleys on the shafts 47 of the drums 23-24 respectively; they are belted to the countershaft pulleys 44-45. Drive is applied via the countershafts and belts to both ends of both drum shafts 47. 48 are water spray pipes perforated to deliver fine sprays of water downwardly over the skins during their ascent between the drums 23-24.

In operation, the beater drums are rotated about 700 revolutions per minute and the linear speed of the chain flights is about six feet per minute. The claw links on the chains are usually located about three feet apart, and the skin boards are about two feet six inches in depth. These speeds and dimensions are subject to variation, but the most advantageous results will be obtained when the figures just stated are approximately observed.

The operation of the machine is as follows: The skins 10 are hung over the boards 11 and clipped or clamped on by means of the devices 12 so that the skins are prevented from accidental slippage during their translation through the machines. The boards so loaded with skins are then fed into the machines over the runway 14, this runway consisting of rails on which the lugs 13 run; this runway carries the boards down to a stop where the lugs 13 are in the path of movement of the chain claws 17. As they ascend, these claws pick up the skin loaded boards one by one and carry them vertically upwards between the beater drums and the mangle rollers. When the skin loaded boards have passed to the upper part of the machine they are carried over by the chains onto the delivery run-

way rails, and they slide along these rails on their lugs 13 as seen in Fig. 1 to a take-off place. Thence they may go through a second treatment in a like machine. In practice, a very few burrs are found along the middle of the back, and consequently that part of the skin which is wrapped over the top edges of the skin boards is not required to be subjected to the beater action. The direction of the rotation of the drums is shown by the arrows in Fig. 1. In this rotation of the drums the wool, hair or fur, is parted and the tubiform beaters are rapidly traversed through the partings; they catch hold of any burr or like entangled material, tearing it out from the fibres and casting it adrift. Shields to pick up this separated matter may be provided as encasements for the upper, outer, and undersides of the drums; these encasements are not shown in the drawings.

What I claim as my invention and desire to secure by Letters Patent is:—

1. In a deburring machine, a pair of endless traveling members spaced apart from each other and disposed for movement through a vertical path, a plurality of skin-carrying members, means for delivering said members in succession to a position between said traveling members, and cooperating means carried by said traveling members and skin-carrying members automatically operative to engage the latter and move them through said vertical path and to release the skin-carrying members after their passage through said path. 100
2. In a deburring machine, a pair of endless traveling members spaced apart from each other and disposed for movement through a vertical path, a plurality of skin-carrying members, means for delivering said members in succession to a position between said traveling members, cooperating means carried by said traveling members and skin-carrying members automatically operative to engage the latter and move them through said vertical path and to release the skin-carrying members after their passage through said path, and means for conducting the skin-carrying members away from said traveling members. 110
3. In a deburring machine, a pair of endless traveling members spaced apart from each other and disposed for movement through a vertical path, a plurality of skin-carrying members, means for delivering said members in succession to a position between said traveling members, cooperating means carried by said traveling members and skin-carrying members automatically operative to engage the latter and move them through said vertical path and to release the skin-carrying members after their passage through said path, and means for spraying water on the skins carried by said members during their passage through the vertical path. 120

4. In a deburring machine, a pair of endless traveling members spaced apart from each other and disposed for movement through a vertical path, a plurality of skin-carrying members, means for delivering said members in succession to a position between said traveling members, cooperating means carried by said traveling members and skin-carrying members automatically operative to engage the latter and move them through said vertical path and to release the skin-carrying members after their passage through said path, deburring means maintained under tension at opposite sides of said skin-carrying members during their passage through the vertical path, and adjustable means between said deburring means for limiting the action thereof.

5. In a deburring machine, a pair of endless traveling members spaced apart from each other and disposed for movement through a vertical path, a plurality of skin-carrying members, means for delivering said members in succession to a position between said traveling members, cooperating means carried by said traveling members and skin-carrying members automatically operative to engage the latter and move them through said vertical path and to release the skin-carrying members after their passage through said path, a pair of deburring drums disposed at opposite sides of said skin-carrying members during their passage through the vertical path, tension means for urging said drums toward each other, a movable wedge-shaped member disposed between said drums for limiting the action of said tension means, and means for adjusting the position of said wedge.

40 In testimony whereof I affix my signature.
WALTER PERKS.
